RUBBING SHOE

Roy J. Champayne, Rockford, Ill.

Application January 2, 1943, Serial No. 471,117

11 Claims.

(Cl. 51—189)

The general object of the invention is to provide a rubbing shoe having a new and improved means for fastening a sheet of rubbing material thereto.

A more detailed object is to provide a rubber shoe having a single device for applying the pressure for clamping each end of the rubbing sheet.

The invention also resides in the novel construction of the shoe which facilitates mounting of the clamping device thereon.

Other objects and advantages of the invention will become apparent from the following detailed description taken in connection with the accompanying drawing, in which

Figure 1 is a side view of the improved rubbing shoe.

Fig. 2 is a similar view with the rubbing sheet detached from the shoe.

Fig. 3 is a fragmentary longitudinal section.

Fig. 4 is a fragmentary perspective view.

In the drawing, the invention is shown incorporated in a rubbing shoe carried by a suitable support 5 and adapted to be actuated either manually or by power. It comprises generally a body 6, a pad 7 secured to the underside of the shoe, and a device for fastening opposite ends of an abrasive paper or other rubbing sheet 8 to the shoe. The body is composed of relatively solid but somewhat resilient material such as leather or firm rubber. As shown, it is a molded substantial flat rectangular block of rubber rounded at one end 9 and having narrow flanges 10 formed along the sides adjacent the top surfaces and a flange 11 overhanging the end 12 disposed in this instance somewhat above the flanges 10. Preferably, the pad 7, which provides a yieldable backing for the abrasive sheet, is composed of softer material such as sponge rubber.

At the other end of the block 6, the pad is inclined upwardly as indicated at 13 and merges with the end 9. Two jaws 14 and 15 extending transversely of the block are molded on or secured to the top of the latter adjacent the rounded end 9. The jaw 14 has a top surface inclined upwardly from the end 9 and separated from the other jaw 15 by a narrow longitudinal slot 16 disposed vertically and adapted to receive one end portion of the abrasive sheet 8. To prevent wearing off of the jaw 15 which contacts the abrasive side of the sheet 8, a strip 17 of metal lies against the face of this jaw and extends down along the upper surface thereof and for a short distance along the top of the block to which it is secured as by screws 18.

Between the slot 16 and the rounded end 9

5 a hole 19 is formed in the block extending transversely across the latter and disposed above the bottom of the slot. One end of a wire rectangle or bail 20 is seated in this hole, being preferably pressed in through a slit 21 cut along the top of the jaw 14. The bail is only slightly wider than the block 6 so as to lie within the edges of the flanges 10 when the free end of the bail is swung upwardly. This end carries a roller 22 which, in the clamping position, is adapted to seat in a slight depression 23 in the block 12 and contact the underside of the flange 11 which constitutes a limit stop.

Preferably, the bail 20 is slightly bowed longitudinally and is shorter in length than the spacing of the block end 12 from the hole 21 when the clamp is released as shown in Fig. 2 so that the block, being composed of material which is somewhat yieldable, will be compressed longitudinally as the roller is rolled around the end 12 and against the flange 11. Thus, the resiliency of the block is utilized to produce a force which is directed longitudinally of the block and applied to the outer jaw 14 along a line disposed above the bottom of the slot 16. Accordingly, this jaw is flexed about the bottom of the slot as a fulcrum and presses the abrasive sheet against the metal surface of the other jaw 15.

30 To attach an abrasive sheet, the bail 20 is swung downwardly as shown in Fig. 2 thereby opening the jaws 14 and 15 to permit the insertion of one end of the sheet 8 between them. Since the side flanges 10 extend across the ends of the slot, they serve to locate the sheet laterally. The sheet is extended around the end 9, along the bottom of the pad, and through the bail. The latter may then be rolled around the end of the pad and upwardly against the flange 11 where it is held in the seat 23 by virtue of the tension under which the bail is placed by the block 6 by virtue of its compressed condition. To remove the sheet, it is only necessary to pull downwardly on the end 24 of the sheet thereby lowering the roller and releasing the jaws.

45 In the clamped positions of the parts shown in Fig. 1, it will be observed that the ends of the abrasive sheet are snubbed around the ends of the block and one end is bent sharply around the jaw 14. In this condition, it has been found that ample gripping pressure is applied to hold the sheet firmly even in service use in power driven sanding tools. The clamp is simple and inexpensive since it requires only one clamping device, namely the bail 20, and yet it is reliable

in operation and permits of ready removal and replacement of the abrasive sheet.

I claim as my invention:

1. A rubbing shoe comprising a block yieldably compressible longitudinally, a transverse rib extending along the top of said block adjacent one end thereof, said rib being slotted longitudinally to receive one end of a rubbing sheet, a bail wider than said block and pivoted on the latter between said slot and the block end and above the bottom of the slot, said bail being shorter than the spacing of its pivot from the other block end and swingable around the latter to compress the block longitudinally whereby to grip one end of said sheet and close said slot to grip the other sheet end, and side and end flanges on said block overlying the sides and end of said bail when the latter is in sheet clamping position.

2. A rubbing shoe comprising a block yieldably compressible longitudinally and having an upwardly opening transverse slot formed adjacent one end for receiving one end of a rubbing sheet, a bail wider than said block and pivoted on the latter between said slot and the block end and above the bottom of the slot, said bail being shorter than the spacing of its pivot from the other block end and swingable around the latter to compress the block longitudinally whereby to grip one end of said sheet and close said slot to grip the other sheet end, and side flanges on said block overlying said bail when the latter is in sheet clamping position.

3. A rubbing shoe comprising a block yieldably compressible longitudinally, transverse jaws extending along the top of said block adjacent one end thereof and separated by a slot adapted to receive one end of a rubbing sheet, and a bail wider than said block and pivoted on the latter between said slot and the block end and above the bottom of the slot, said bail being shorter than the spacing of its pivot from the other block end and swingable around the latter to compress the block longitudinally whereby to grip one end of said sheet and close said slot to grip the other sheet end.

4. A rubbing shoe comprising a resilient block, a bail pivoted on one end of the block and swingable around the other end of the block to compress it longitudinally and grip one end of an abrasive sheet, and jaws on said first mentioned block end receiving the other end of said sheet and closed automatically under the compressive force applied by said bail.

5. A rubbing shoe comprising a block of resilient material having an upwardly opening slot extending across one end thereof, a bail pivoted in said block between one end thereof and said slot and above the bottom of the latter, and a roller on the free end of said bail movable around the other end of said block and operable to compress the block longitudinally to close said slot and grip a rubbing sheet disposed therein.

10. 6. A rubbing shoe comprising a block having a pair of jaws projecting upwardly at one end to receive one end portion of an abrasive sheet, one of said jaws being movable, and a bail pivoted on said block end and swingable around the other end to clamp the other end of said sheet and simultaneously actuate said movable jaw to clamp said first mentioned sheet end.

7. A rubbing shoe for carrying a rubbing sheet on the underside thereof comprising a block having a clamp at one end for receiving one end of said sheet, and a member movable around the other end of the block to grip the other sheet end and simultaneously actuate said clamp to grip the first mentioned sheet end.

25. 8. A rubbing shoe for carrying a rubbing sheet on the underside thereof comprising a block having a clamp at one end opening upwardly to receive one end of said sheet, and a member movable around the other end of the block to grip the other sheet end and simultaneously actuate said clamp to grip the first mentioned sheet end.

9. A rubbing shoe comprising a resilient block, a bail pivoted on one end of the block and swingable around the other end of the block to compress it longitudinally and grip one end of an abrasive sheet, and jaws on said first mentioned block end receiving the other end of said sheet and closed automatically under the compressive force applied by said bail.

10. A rubbing shoe comprising a resilient block, a bail pivoted on one end of the block and swingable around the other end of the block to compress it longitudinally and grip one end of an abrasive sheet, and jaws on said first mentioned block end receiving the other end of said sheet and closed automatically under the compressive force applied by said bail.

11. A rubbing shoe comprising a block composed of resilient material, and a bail pivoted on said block and swingable around one end of the block to compress the block and derive a force for gripping a rubbing sheet disposed between the block end and the free end of the bail.

55. ROY J. CHAMPAYNE.
